DUMPING SCRAPER

Albert G. Gurries, Gilroy, Calif., assignor to
Be-Ge Manufacturing Company, Gilroy, Calif.,
a copartnership comprising Albert G. Gurries
and James A. Bussert

Application March 31, 1939, Serial No. 265,207

7 Claims. (Cl. 37—129)

This invention relates to carrying rear-dump scrapers, and particularly represents improvements over the dirt-retaining or apron structure of my copending application #254,878, filed February 6, 1939.

In this previous structure, the apron was fixed on the frame, and in order to properly cooperate with the bowl when the latter moved up to a carrying position, was necessarily disposed where it tended to interfere with the desired free movement of the dirt into the bowl as the latter was in scraping position.

It is therefore the major object of this present invention to provide a closure apron for the bowl so arranged and mounted that when the bowl is in scraping position, the lower end of the apron is held sufficiently advanced so as to be well clear of dirt entering the bowl. When the bowl is lifted to carrying position, however, the apron assumes a proper cooperating position with the bowl; the movement of the apron from one position to the other being controlled by the movement of the bowl itself, so that no additional mechanism is necessary for operating the apron.

When used for highway maintenance service, for which this scraper is particularly designed, and when scraping dirt slides off highways, for instance, the blade of the bowl must approach close to but not cut into the hard surface of the highway. Usually this requires very careful attention on the part of the operator in setting the blade at the proper level after each scraping operation, which if repeated many times as is frequently necessary, slows down the work to an appreciable extent.

It is therefore another object of my invention to provide an adjustable and easily operated means for positively limiting the downward movement of the bowl relative to the ground, irrespective of the functioning of the bowl control mechanism, so that extreme care on the part of the operator is unnecessary.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of my improved scraper, partly in section and showing the bowl

lowered to a scraping position adjacent ground or road level.

Figure 2 is a sectional elevation showing the bowl raised to carrying position.

Figure 3 is a top plan view of the apron detached.

Figure 4 is a fragmentary sectional plan of a bowl-control hydraulic cylinder unit, showing the adjustable piston stop.

Referring now more particularly to the characters of reference on the drawings, the frame of the scraper comprises spaced side beams 1 supported intermediate their ends on wheels 2 disposed outside the beams. Ahead of the wheels the beams are connected by a cross beam 3; a rigid tongue 4, adapted at its forward end for supporting connection with a tractor, extending forwardly from the cross beam.

The bowl 5 of the scraper, preferably of the same configuration as in said copending application, is disposed between the side beams rearwardly of the cross beam and is supported at its back from the side beams 1 rearwardly of the wheels, by a cross shaft 6. The bowl includes side plates 7 and a scraping blade 8 terminating substantially flush with the plates at their forward edge.

The rotation of the bowl, to move it between scraping, carrying and dumping positions and vice-versa, is controlled as before by hydraulic units, one on each side. Each unit includes a cylinder 9, a piston 10 therein and a piston rod 11 projecting rearwardly from the cylinder and pivoted on the adjacent side plate of the bowl near its rear end and above pivot shaft 6. The cylinder at its forward end is provided with laterally projecting trunnions 12 turnable in mounting ears 13 upstanding from adjacent side beam 1 near cross beam 3.

An adjustment screw 14 is threaded into the forward end of the cylinder in axial alignment with the piston rod and engages the piston after predetermined forward movement thereof as shown in Fig. 4. Since such forward movement obviously controls lowering movement of the front end and blade of the bowl, it will be seen that positive stopping of such forward movement by the screw 14 likewise positively limits downward movement of the blade irrespective of the hydraulic pressure supplied to the cylinder rearwardly of the piston, and the blade may thus be held at any desired level relative to the ground without any attention on the part of the operator being necessary.

The front apron for the bowl is in the form of

a plate 15 extending substantially the full width of the bowl between the side plates. Intermediate its ends, the plate on its front side is reinforced by vertical ribs 16. These ribs at the top are pivoted by pins 17 in the top of housings 18 which upstand and project rearwardly from cross beam 3.

Rods 19 are pivoted on the ribs below the pivot pins and slidably project through the front walls 10 of the housings. Compression springs 20 are disposed about the rods between the ribs and front walls, the springs thus acting to swing the apron rearwardly. Such rearward movement is limited by adjustable nuts 21 on the rods ahead of 15 the housings.

The apron plate at its ends is provided with other vertical ribs 22 serving as supports for rollers 23 disposed laterally out from said ribs and a certain distance below pivot pins 17. The 20 front edges of the side plates 7 of the bowl are provided with outwardly projecting flanges 24 which form cam tracks on the roller ride.

The upper portion of the cam tracks, which engage the rollers when the blade 8 is in scraping 25 position, are concentric with the bowl pivot 6, so that with turning of the bowl to various scraping levels, there will be no movement of the apron. When the rollers are thus engaged, the apron is held at a forward slope to its lower end, as shown 30 in Fig. 1, so that such end is ahead of any dirt "boiling up" in front of the blade with the advancing movement of the bowl and blade. The pivot point of the apron is at such a height relative to the depth of the latter that its lower end 35 is then adjacent the lower edge of the cross beam 3.

The lower portion of the cam tracks is disposed in such relation to the bowl pivot that as the latter swings up to carrying position, the 40 rollers, while still engaging the tracks, will move rearwardly as urged by springs 21, until when the bowl finally assumes a carrying position, the apron projects between the side plates and engages the blade as shown in Fig. 2, thus forming 45 an efficient closure and dirt retainer for the front end of the bowl. It will be noted, however, that nothing but the yieldable springs forces the apron to such blade engaging position, so that in the event that an obstruction at the blade should 50 prevent actual engagement of the apron therewith, no harmful strains will be placed on the apron or its operating parts.

When the bowl is swung to a dumping position and the cam tracks leave the rollers, the nuts 55 21 limit rearward movement of the apron so that the rollers remain in position to be reengaged by the cam tracks as the bowl is again swung down to an operating position.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A scraper including a supporting frame, a bowl mounted in the frame for vertical movement at its forward end to dispose said end in scraping and relatively raised carrying positions al-

ternately, an apron mounted on the frame in front of the bowl to form a closure with the bowl at its front end when the latter is in carrying position and means between the bowl and apron to shift the lower end of the latter forwardly by lowering movement of the front end of the bowl; said last named means comprising a cam track on the bowl at the front thereof and an element on the apron engaging said track. 5

2. A scraper including a supporting frame, a bowl mounted on the frame for vertical movement at its forward end to dispose said end in scraping and carrying positions alternately, an apron disposed in front of the bowl, means pivoting the apron at the top on the frame in position to form a closure for the front end of the bowl when the latter is in carrying position and means between the bowl and apron to swing the latter forwardly with lowering of the front end of the bowl to a scraping position; said last named means comprising a roller mounted on the side of the apron below the pivot thereof and a cam track on the front edge of the bowl normally engaging the roller. 20

3. A structure as in claim 2, in which said cam track, for an extent corresponding to movement of the front end of the bowl between the limits of its scraping levels, being concentric with the pivot of the bowl. 25

4. A scraper including a supporting frame, a bowl mounted in the frame for movement in a vertical plane to dispose its forward end in scraping and carrying positions alternately, an apron disposed in front of the bowl, means pivoting the apron at the top on the frame in position 30 to form a closure for the front end of the bowl when the latter is in carrying position, said means including transversely spaced housings mounted on the frame, rods connected to the apron below the pivot means and projecting forwardly through the front wall of the housings with a sliding fit, compression springs about the rods between the apron and the front wall of the housings and acting to yieldably swing the apron rearwardly, stops on the rods ahead of the housings to limit rearward movement of the apron and means between the bowl and apron to swing the latter forwardly against the resistance of the springs with lowering movement of the front 45 end of the bowl to a scraping position. 50

5. A scraper including a supporting frame, a bowl mounted in the frame for vertical movement at its forward end to dispose said end in scraping and relatively raised carrying positions alternately, an apron mounted on the frame in front 55 of the bowl to form a closure with the bowl at its front end when the latter is in carrying position and means between the bowl and apron to shift the lower end of the latter forwardly a pre-determined distance by lowering movement of the front end of the bowl from a carrying position to the topmost scraping position and to hold the apron stationary with further lowering movement of the bowl. 60

6. A scraper including a supporting frame, a bowl mounted on the frame for vertical movement at its forward end to dispose said end in scraping and carrying positions alternately, an apron disposed in front of the bowl and mounted on the frame in position to form a closure with the 70 bowl at its front end when the latter is in carrying position and movable forwardly from its closure forming position, and independent separable elements on the bowl and apron engageable with each other between carrying and scraping posi- 75

tions of the bowl to shift the lower end of the apron forwardly by lowering movement of the bowl from a carrying position.

7. A scraper including a supporting frame, a bowl mounted in the frame for vertical movement at its front end to enable said end to be moved from a scraping to a carrying position and thence farther upwardly for dumping, an apron disposed in front of the bowl, means pivoting the apron at the top on the frame in position to form a closure for the front end of the bowl when the latter is in carrying position, a roller mounted on

the side of the apron, a cam track on the front edge of the bowl engaging the roller between carrying and scraping positions of the bowl and arranged to cause the apron to be shifted forwardly with lowering of the bowl from a carrying position, yieldable means tending to swing the apron rearwardly and stop means definitely limiting such rearward movement of the apron to an extent such that the roller remains in position to re-engage the cam track upon the lowering of the bowl from a dumping position. 5
